UNITED STATES PATENT OFFICE.

CHARLES H. HOWARD, OF SAUGUS, MASSACHUSETTS, ASSIGNOR TO PAPER PRODUCTS MACHINE COMPANY, OF BOSTON, MASSACHUSETTS, A CORPORATION OF MASSACHUSETTS.

BAG-FILLING MACHINE.

Original application filed October 26, 1918, Serial No. 259,882. Divided and this application filed December 3, 1920. Serial No. 427,986.

To all whom it may concern:

Be it known that I, CHARLES H. HOWARD, a citizen of the United States, residing at Saugus, in the county of Essex and State 5 of Massachusetts, have invented an Improvement in Bag-Filling Machines, of which the following description, in connection with the accompanying drawings, is a specification, like characters on the drawings representing 10 like parts.

The invention to be hereinafter described relates to machines for filling bags and other containers, and is a division from my co-pending application Serial No. 259,882, filed 15 October 26, 1918.

In carrying the invention into practical effect, in the present instance, the paper bags are conducted by a conveyor to a filling station where a charge of material, such, 20 for example, as cement, is fed into a weighing receptacle, and after a predetermined weight has entered said receptacle, the supply of material is automatically cut off. In the course of the weighing of the material 25 in the receptacle, the latter is automatically moved down into the bag or container toward the bottom thereof, and when nearly to the bottom, the lower end of the receptacle is opened to discharge the material 30 into the bag. Then the weighing receptacle is elevated out of the bag. The construction and operation are such that the charge of material is introduced into the bag with a minimum amount of dust, thereby effecting 35 an accurate delivery of the weighing charge with economy of material and with comfort to the operator of the machine.

After the bag has received a predetermined charge of material, it is conveyed by 40 the bag carrier to a second station where a cap of paper or other suitable material may be introduced into the bag and superposed on the charge of material therein. The upper portions of the bag are folded over 45 onto an adhesive coating on the cap, and into adhesive engagement therewith. Then the bag is conveyed by the carrier to a third station. Then portions of the bag are folded over into adhesive engagement with an adhesive coating on the cap. Then the bag 50 is conveyed by the carrier to a third station where a waterproof adhesive is applied to

the portions of the bag which have been folded over at the previous station. Thereupon, other portions of the bag are folded down onto the waterproof adhesive and secured thereto. After the bag has been closed and sealed, it is advanced by the carrier to a third station and is discharged from the carrier. 55

Since the mechanism for applying the caps and closing the upper end of the bag is shown, described and claimed in said co-pending application, it is unnecessary to show and describe this mechanism in detail herein. 60

The character of the invention will be best understood by the following description of one good form thereof shown in the accompanying drawings, wherein:—

Fig. 1 is a front elevation of the machine 70 shown herein as one embodiment of the invention;

Fig. 2 is a front elevation of the hopper for receiving the materials;

Fig. 3 is a rear elevation of the machine;

Fig. 4 is a rear elevation of the hopper;

Fig. 5 is an end elevation of the machine looking toward the right of Fig. 1;

Fig. 6 is an end elevation looking toward the left of Fig. 1, a portion of the hopper 80 being broken away to disclose feed screws therein;

Fig. 7 on an enlarged scale is a vertical section through the bag conveyor;

Fig. 8 is an end elevation of the construction shown in Fig. 7, certain parts being shown in section;

Fig. 9 on an enlarged scale is a view partly in elevation and partly in vertical section of the feeding tubes, the conveyors therein, 90 the weighing receptacle, and the counter-balancing weights for the receptacle;

Fig. 10 on an enlarged scale is a horizontal section taken on line 10—10 of Fig. 9;

Fig. 11 is a view partly in elevation and 95 partly in vertical section of the feeding tubes and weighing receptacle showing the valves or gates for controlling the discharge therefrom;

Fig. 12 on an enlarged scale is an elevation showing portions of the hopper, one of the feed tubes, the clutch and gear box, the electrically controlled toggle box, and a system of links and levers co-operating

therewith for controlling various devices of the machine;

Fig. 13 on an enlarged scale is a horizontal section taken on line 13—13 of Fig. 6;

Fig. 14 on an enlarged scale is a horizontal section taken on line 14—14 of Fig. 1;

Fig. 15 on an enlarged scale is a vertical section taken through the toggle box;

Fig. 16 is a vertical section taken on line 16—16 of Fig. 15;

Fig. 17 is a vertical section taken on line 17—17 of Fig. 3 showing clutches and gears in the clutch and gear box;

Fig. 18 is a vertical section taken on line 18—18 of Fig. 20;

Fig. 18^c is a sectional detail of the single rotation clutch in the transmission for the bag carrier;

Figs. 18^b and 18^c are perspective details of the pin and latch of said clutch;

Fig. 19 is a vertical section taken on line 19—19 of Fig. 17;

Fig. 20 is a vertical section taken on line 20—20 of Fig. 17;

Fig. 21 is a plan of the bag holder showing its cover closed;

Fig. 22 is a view partly in section and partly in elevation of the bag holder showing the cover open;

Fig. 23 is a view partly in section and partly in elevation of a stop device for the bag carrier;

Fig. 24 is a sectional detail of the stop device shown in Fig. 23.

Referring to the drawings, the machine shown therein as one good form of the invention may be provided with any suitable frame for supporting the various instrumentalities of the machine. In the present instance of the invention, this frame comprises bases 1 (Figs. 1 and 3) supporting elongated front and rear frames 3 for supporting the bag carrier. Rising from said side frames is a tower 5 for supporting the mechanism at the bag filling station, and also rising from said side frames are posts 7 supporting an upper horizontal frame 9 carrying parts of the mechanism at the station for applying the caps to the bags and at the station for folding over and sealing the upper portions of the bag.

Any suitable mechanism may be provided for receiving the bags and conveying the same to the successive stations. For this purpose, in the present instance of the invention, a carrier is provided comprising sprocket chains 11 (Figs. 7 and 8) on sprocket wheels 13 mounted on shafts 15 journaled in bearings in the front and rear frames 3, referred to. These sprocket chains comprise links 15 connected by shafts 17 provided with flanged rollers 19 guided by tracks 21 carried by the front and rear frames 3, and serving effectively to guide the sprocket chains in an elliptic-like orbit.

The sprocket chains may be equipped with suitable means for properly receiving, holding and discharging the bags. This means, in the present instance, comprises a series of holders 23 (Figs. 7 and 8) mounted on

and secured to certain links of the sprocket chains at suitable intervals. Each of these holders may have a bottom 25 which may conveniently be the link carrying the holder,

and end walls 27 connected by a side wall 29.

To facilitate reception and discharge of the bag, the opposite side wall 31 may be movably mounted with respect to the holder.

In the present form of the invention, this movable side is provided with arms 33 connected to a boss 35 adapted to rock on one

of the shafts 17 connecting the links of the sprocket chains. To automatically open

and close the side 31 at the times required, the boss 35 may have an arm 37 fast

thereon projecting inward from the sprocket chain, and provided with rollers 39 adapted

to travel in opposed cam guides 41 carried

by a web 43 secured to members 45 receiving

the sprocket wheel shafts 15, referred to,

and secured to X-shaped frames 47 (Fig. 8) secured to and serving to brace the front

and rear frames 3 of the machine.

The shape of the cam guides 41 is such that the sides 31 of the bag holders will be open when at the receiving end of the machine, as shown at the right of Fig. 1, will be closed in traversing the upper horizontal run of the sprocket chains, will be

automatically opened when at the delivery end of the machine, as shown at the left of Fig. 1, and will be closed when traversing the lower horizontal run of the sprocket chains.

To assist in folding the upper end portion of the bag and to maintain said portions in their folded relation while the bag is

conveyed from the folding station to the discharge end of the machine, each holder

may be provided with a cover comprising sections 49 (Figs. 21 and 22) having their outer edges provided with bosses 51 ful-

crumed on shafts 53 secured to boss brackets 55 at the upper ends of the sides 29 and 31 of the holder.

To normally hold the cover sections in open positions, as shown in dotted lines in Fig. 31, coil springs 57 may be

provided encircling the shafts 53, and having ends secured to spurs 59 on the bosses 51, and portions intermediate said ends secured to certain of the bosses 55. The

construction is such that the springs will tend to open the cover sections, but will allow closing thereof at the times required.

To secure the cover sections in closed position during their transit from the folding station to the discharge end of the machine

they may be provided with suitable locking means, in the present instance, consisting

of spring-pressed latches 61 on one of the

sections adapted to enter slots 63 in ears 64 on the other section. The construction is such that when the bag holder reaches the discharge end of the machine, the hinged side 81 thereof will swing outwardly and withdraw the latches from the slots and allow the springs to open the cover sections.

The bags may be introduced in the bag holders of the bag carrier manually or automatically as desired, so that as each holder passes from the receiving end of the machine, it will convey a bag to the filling station. Suitable detector means may be provided to automatically arrest the machine, in case for any reason a bag should fail to be introduced into one of the bag holders. This detector means, in the present instance of the invention, comprises a detector finger 65 (Figs. 23 and 24) pivotally mounted on the wall 27 of each bag holder, and adapted to project through a slot 67 into the holder. This finger carries a bridge contact 69 at one end thereof adapted to engage a pair of fixed contacts 71 carried by a bracket 73 (Fig. 1) mounted on one of the frames 3 adjacent the receiving end of the machine. These contacts may be connected by wires 75 with an electrical cut out in the driving mechanism for the machine, but since this electrical cut out is of usual construction, it is deemed unnecessary to show the same herein. The construction is such that when a bag is in the holder, the bridge contact 69 is retracted so that it will not engage the fixed contacts 71 as the bag holder passes the bracket 73. If, however, there is no bag in the holder the detector finger 65 will gravitate to a position such that the bridge contact 69 will engage the fixed contacts 71 and complete the circuit to the electrical cut out, thereby opening the same and arresting the machine.

Having described the bag holders and the carrier therefor, next will be described the means for filling the bags. This means, in the present instance, comprises a hopper 77 (Figs. 1-4) mounted on the top of the tower 5, referred to, and provided with a tapered bottom 79. Suitable means may be provided for feeding the material from the hopper. To accomplish this, in the present instance, a pair of tubes 81 (Figs. 9 and 11) are provided depending from and communicating with the hopper and in closely assembled relation. It is desirable that the materials shall be positively fed from the hopper downward through these tubes. For this purpose, the tubes are provided with a pair of feed screws 83 on shafts having lower ends journalled in bearings 85 suitably supported adjacent the lower ends of said tubes, and journalled in bearings in a member 87 (Fig. 6) carried by a horizontal support 89 at the top of the hopper.

To rotate said feed screws, their upper ends

may have beveled gears 91 fast thereon meshing with beveled gears 93 on a horizontal shaft 95 journalled in bearings at the top of said hopper. One end of said horizontal shaft has a bevel gear 97 fast thereon meshing with a bevel gear 99 fast on the upper end of a vertical shaft 101 projecting downward along the hopper through a bearing 103 in a bracket secured to the tower 5, and thence along the tower into the clutch and gear box 105 carried by a frame 107 on brackets 109 (Figs. 3 and 6) secured to one of the frames 3, referred to. On the lower end of the vertical shaft 101 in the clutch and gear box is a bevel gear 111 (Fig. 19) meshing with a bevel gear 113 fast on a sleeve shaft 115 journalled in a bearing 117 in said box. The main driving shaft 119 of the machine projects through the sleeve shaft 115 and through a bearing 121 outward beyond said box, where it receives a pulley 123 adapted to be driven by a belt from an electric motor or other suitable source of power.

To drive the feed screws at the times required, a clutch member 125 (Fig. 19) is mounted on the main driving shaft 119 and is adapted to rotate therewith, but slide longitudinally thereof. The clutch member has teeth 127 for engagement with opposed teeth 129 on one end of the sleeve shaft 115. To shift the clutch, a yoke 131 is connected to the clutch member 125, and has arms 133 adapted to receive a rod 135 slidably mounted in upper extensions of the bearings 117 and 121. A block 137 (Fig. 17) fast on the rod 135, has studs 139 projecting therefrom received by forks 141 fast on a rock shaft 143 mounted in a bearing at the top of the box 105. A toothed sector 145 fast on the shaft 143 meshes with a toothed sector 147 fast on a shaft 149 mounted in bearings at the top of the box 105. One end of the shaft 149 projects beyond said box and receives a crank 151 (Figs. 12 and 17) adapted to be operated, as more fully hereinafter described.

Suitable means may be provided to receive the material fed positively by the feed screws from the tubes 81, and to deliver a predetermined charge from the feed tube into the bag to be filled at the station beneath the feed tubes. This means, in the present instance of the invention, comprises a weighing receptacle 153 (Figs. 9 and 11) conveniently of general elliptic form sufficiently large to receive the feed tubes with a substantial space between said receptacle and tubes. The lower end of the weighing receptacle may be provided with valve means for controlling the discharge of the material from the receptacle into the bag. This valve means, in the present form of the invention, comprises a pair of gates 155 hinged to the lower end of the recep-

tacle, and preferably converging downward and having their lower edges meeting when closed, as shown in Fig. 11. Suitable means may be provided for opening and closing these gates at the times required. This means, in the present instance, comprises fingers 157 at the lower ends of rods 159 projecting upward through spaces between the feed tubes and the receptacle, and 10 adapted to rock in bearings 161 secured to the lower end of the receptacle and in bearings 163 secured to the upper end of the receptacle. These rods may be rocked to turn the fingers inward to close the gates 15, and may be rocked outward to allow the gates to swing open from the weight of the material thereon. It is desirable that the gates should be closed when the receptacle approaches its upward limit of movement, and should be opened as the receptacle approaches the bottom of the bag. To accomplish this, in the present form of the invention, the rods 159 are provided at their upper ends with arms 165 carrying 25 rollers 167 adapted to engage upper cams 169 mounted on cross bars 171 (Fig. 12) carried by the tower, and adapted to engage lower cams 173 (Figs. 1, 12 and 13) mounted on cross bars 175 carried by the 30 tower. The construction is such that as the receptacle approaches its upper limit of movement, the arm rollers 167 will wipe along the cams 169 and close the gates 155, and when the receptacle approaches its 35 lower limit of movement, the arm rollers will wipe along the cam 173 and allow opening of said gates.

Suitable means may be provided to counterbalance the weight of the receptacle. To 40 accomplish this, in the present instance, the receptacle is provided with lugs 177 (Fig. 9) adjacent the upper end thereof, and connected to links of sprocket chains 179. These chains pass around upper sprocket 45 wheels 181 on shafts 183 mounted in brackets 185 projecting laterally from a neck 187 adjacent the juncture of the hopper with the feed tubes. The sprocket chains also pass around lower sprocket wheels 189 on shafts 191 mounted in brackets 193 and 195 respectively carried by the frame of the machine.

Secured to the sprocket chains are tare 50 weights 197 in tubes 199 carried by sleeves 201 on cross bars 203 (Fig. 13) on the tower. These tare weights will serve to counterbalance the weighing receptacle when empty. As the material is fed into the receptacle, the latter will lower and cause the tare 55 weights to move upward in their tubes.

Suitable means may be provided for accurately weighing the charge fed into the receptacle and insuring the delivery from the receptacle into the bags of charges of equal predetermined weights. This means, in the present instance of the invention, com-

prises series of weights 205, 207, 209 and 211 which may be progressively brought into play to gradually check the lowering movement of the weighing receptacle until the final weights 211 come into play. Then the feed of material to the receptacle is automatically shut off by means to be described, and the charge in the receptacle is delivered into the bag. In the present form of the invention, the series of weights are mounted in the tubes 199 and are supported on steps 213 formed in said tubes at intervals. The construction is such that as the receptacle moves downward and the tare weights move upward, the latter will move to and lift the lowest weights 205 from their seats and then as the tare weights continue to move upward, the weights 205 will lift the weights 207 from their seats, and the weights 207 will lift the weights 209 from their seats, and finally the weights 209 will lift the weights 211 from their seats. On the occurrence of this event, further feed of material into the weighing receptacle is arrested.

Next will be described the means for automatically cutting off the feed of material from the feed tubes to the weighing receptacle when the upper weights 211 are lifted from their seats. This means, in the present instance, comprises a dog 215 (Figs. 1, 9 and 10) pivotally mounted in a box 217 secured to one of the weight supporting and guiding tubes 199. This dog is adapted to project through an opening in said tube and engage the bottom of one of the upper weights 211 when the latter is resting on its seat, said dog being held against said weight by a coil spring 218 having one end attached to the dog and the other end attached to the box 217. The upper end of this dog carries a bridge contact 219 adapted to connect a pair of fixed spring contacts 221 secured to posts 223 attached to the outer wall of the box. These posts are connected by conductors 225 with the coils of a magnet 227 (Fig. 15), a battery 229 or other suitable source of electricity being connected into one of said conductors. The magnet 227 may be mounted in a box 231 secured to the toggle box 233 (Figs. 1 and 15) mounted on one of the frames 3, referred to. Co-operating with the magnet 227 is an armature 235 connected to a pin 237 projecting into the toggle box 233.

The feed tubes may be provided with suitable valve means which may be automatically closed by an instrumentality to be described which is set in operation on energization of the magnet and thrusting of the armature pin 237 into the toggle box. This valve means, in the present instance, comprises a pair of gates 239 (Figs. 9 and 11) common to the two feed tubes 81 and hinged thereto at the lower ends thereof. These

gates are adapted to converge downward and have their free edges meet when in closed position, and are swung outward to permit feed of material from the feed tubes to the weighing receptacle. To operate these gates, they may have arms 241 at opposed ends thereof connected by links 243 with heads 245 on the lower ends of rods 247 projecting vertically upward in spaces between the feed tubes and weighing receptacle, as will be noted in Fig. 9. The upper ends of said rods carry rollers 249 entered into elongated openings in rock levers 251 (Figs. 1, 3 and 12) fast on a shaft 252 on brackets 253 secured to and depending from the neck 187, referred to. An arm 254 fast on shaft 252 is connected by a rod 255 with one end of a rock lever 257 fast on a rock shaft 259 journalled in bearings mounted on the tower, an arm 260 fast on the rock shaft 259 being connected by a rod 261 with the upper end of a plunger 263 which projects through boss bearings 265 and 267 on the toggle box 233. The plunger is normally urged upward by a coil spring 269 confined between the upper end of the boss bearing 265 and a collar 271 secured to the plunger.

Suitable means may be provided for energizing said spring-pressed plunger and releasing the same. To accomplish this, in the present instance, a toggle may be provided comprising pairs of links 273 and 275, the former having their outer ends pivotally connected to the boss bearing 265, and the latter having their outer ends pivotally connected to a block 277 fast on the plunger. The inner ends of the toggle links 273 and 275 may be connected by a pin 279. When this toggle is straightened, it will draw the plunger down and compress the spring 269, and when buckled, it will allow the spring to shift the plunger upward. To lock the toggle in its straightened position, a link 281 may have one end connected thereto and its opposite end connected to an arm 283 secured to a shaft 285 mounted in a boss bearing 287 at the top of the toggle box. The arm 283 has a toe 289 at the lower end thereof adapted to be engaged by a bell-crank latch 291 pivotally mounted in the toggle box and normally held against said toe by a coil spring 293. Said latch has an arm 295 which projects upward in the path of the armature pin 237, referred to. The coil spring 297 having one end connected to the arm 283 and its opposite end connected to the boss bearing 265, tends to rock the arm 283 to the left of Fig. 15 and buckle the toggle links from their position shown in full lines to their position shown in dotted lines in Fig. 15.

The construction described is such that when the weighing receptacle moves downward sufficiently far to lift the upper weights 211 from their seats, the spring 218 will

rock the dog 215 to the left (Figs. 9 and 10) and cause the bridge contact 219 to engage the spring contacts 221. This will complete the circuit to the electric magnet 227, and the latter will attract the armature 235, push the pin 237 to the left of Fig. 15, and release the latch 291 from the toe 289 of the arm 283. This will allow the spring 297 to rock the arm 283 and link 281 to the left of Fig. 15 and buckle the toggle. This will release the spring 269 which will shift the plunger 263 upward and through the rod 261, rock levers 260 and 257, rod 255, rock levers 254 and 251 and rods 247, will close the feed tube gates 239, thereby interrupting the feed of material from said tubes to the weighing receptacle.

The shifting of the spring-pressed plunger as described may also be utilized to shift the clutch member 125, referred to, for interrupting the rotation of the feed screws in the feed tubes simultaneously with the closing of the gates for the latter. To accomplish this, the rock shaft 259, referred to, may have an arm 298 fast thereon connected by a rod 299 with the crank 151 on the shaft 149 in the clutch and gear box 105. The upward movement of the spring-pressed plunger 263 will operate through the rod 261, rock lever 298, rod 299, crank 151, shaft 149, toothed sectors 147 and 145 and arms 141 to shift the block 137 to the left of Fig. 19. This will energize a coil spring 301 confined between said block and one of the arms 133 of the yoke 131, referred to, until a cam incline 303 of said block engages and trips a trigger 305 having a shoulder engaging the arm 133. This will allow the coil spring 301 to shift the yoke sharply to the left of Fig. 19 and disconnect the teeth 127 of the clutch member from the teeth 129 of the sleeve shaft 115 in the transmission to the feed screws, thereby automatically arresting the latter.

Having described the means for automatically closing the feed tube gates and arresting the feed screws after a charge of predetermined weight has entered the weighing receptacle, next will be described suitable means co-operating with the roller arms 165 and rods 159, referred to, for rocking the same to allow opening of the gates 155 of the weighing receptacle from the weight of the material thereon. When the weighing receptacle has come to rest after a predetermined charge has entered therein, it is in a position such that the roller arms 165 are somewhat above the lower fixed cams 173, referred to.

Next will be described means for automatically moving the weighing receptacle downward so that the rollers of the arms 165 may wipe along the lower fixed cams 173 and rock the rods 159 and arms 157 to effect the opening of the weighing receptacle.

gates 155. To this end one of the shafts 191 for one of the lower sprocket wheels 189 may have a spiral gear 307 (Fig. 17) fast thereon meshing with a spiral gear 309 fast 5 on a shaft 311 journalled in a bearing in a boss 313 on the clutch and gear box 105. A bevel gear 315 fast on the shaft 311 meshes with a bevel pinion 317 and a bevel pinion 319 (Fig. 20) loose on a shaft 321 10 parallel to the shaft 119, referred to, and journalled in bearings 323 and 325 in the clutch and gear box.

To drive the shaft 321, a gear 327 is mounted fast thereon and meshes with a 15 gear 329, as will be noted in Fig. 17, fast on a sleeve shaft 331 journalled in the bearing 121 referred to, and receiving the main driving shaft 119.

To connect the sleeve 331 with the main 20 driving shaft 119 at the times required, the clutch member 125, referred to, may have teeth 333 thereon adapted to engage teeth 335 on one end of said sleeve shaft. The construction is such that when the clutch 25 member 125 is given its shifting movement to interrupt the rotation of the feed screws, it causes the teeth 333 to engage the teeth 335, and thus the gears 329 and 327 and the shaft 321 is rotated, but since the pinions 317 30 and 319 are loose on the shaft 321, neither of them will be rotated until connected therewith. To accomplish this the clutch member 337 (Fig. 20) may be provided on the shaft 321 and rotate therewith, but be susceptible of a slight sliding movement longitudinally thereof. This clutch member has teeth 339 adapted to engage teeth 341 on the bevel pinion 317.

The clutch member is shifted to connect 40 the bevel pinion 317 with the shaft 321 at the time the clutch member 125 is shifted to connect the main driving shaft with the sleeve shaft 331. As a consequence, on such shifting of the clutch member 125, the bevel 45 pinion 317 will be rotated, and the latter will rotate the bevel gear 315, the shaft 311, the spiral gears 307 and 309, and thus impart rotation to one of the lower sprocket 50 wheels 189, thereby causing one of the sprocket chains 179 to travel and move the weighing receptacle downward. To insure equal 55 movements of both of the sprocket chains 179, the shafts 183 for the upper sprocket wheels 189 may be connected by suitable 60 transmission means, in the present instance, comprising bevel gears 343 (Figs. 1 and 14) fast on the shafts 183 meshing with bevel gears 345 fast on the cross shaft 347 journalled in bearings 349 carried by the neck 65 187 at the juncture of the hopper with the feed tubes.

The downward movement thus imparted to the weighing receptacle will cause the rollers 167 on the arms 165 to rock the rods 159 and arms 157 and allow opening of the

gates 155, thereby allowing the charge of material in the weighing receptacle to pass into the bag. When the weighing receptacle is in its lowest position, the gates 155 are closely adjacent to the bottom of the bag. After the gates have been opened as described, it is desirable to elevate the weighing receptacle to withdraw the walls thereof upward between the charge of material and the walls of the bag, thereby to transfer the 75 charge to the bag without dust and loss of material.

Therefore, next will be described suitable means for elevating the weighing receptacle. This means, in the present instance, comprises clutch teeth 351 (Fig. 20) on the clutch member 337 referred to, adapted to engage clutch teeth 353 on the bevel pinion 319. When the clutch member is shifted to the right of Fig. 20, it will disconnect the bevel pinion 317 from the shaft 321 and connect the bevel pinion 319 with said shaft, and thereby cause the bevel gear 315, shaft 311 and spiral gears 307 and 309 to rotate in a direction to elevate the weighing receptacle.

Suitable means may be provided for automatically shifting the clutch member 337 to elevate said receptacle. To accomplish this, in the present instance, the weighing receptacle is provided with a tappet 355 (Fig. 9) 85 adjacent the upper end thereof and conveniently forming a continuation of one of the lugs 177. This tappet when travelling downward is adapted to engage a rock lever 357 (Figs. 1, 3 and 12) fast on a shaft 358 carried by a bracket 359 secured to one of the cross bars 175, referred to, on the tower. A rock lever 390 fast on the shaft 358 is connected by a rod 361 with a crank 363 on an end of the shaft 364 projecting outward from the clutch and gear box 105. The shaft 364 has a pair of arms 365 (Figs. 17 and 20) thereon having forked ends receiving rollers 367 on pins on a block 369 fast on a rod 371 adapted to slide longitudinally in upper extensions of the bearings 323 and 325, referred to. The clutch member 337 is connected to a yoke 373 having arms 375 receiving the rod 371. A coil spring 377 is confined between the block 369 and one of the arms 375, and a coil spring 379 is confined between said block and the other arm 375.

The construction is such that as the weighing receptacle is moved downward by the mechanism described, the tappet 355 will engage the rock lever 357, and the latter operating through the shaft 358, arm 390, rod 361, crank 363, and fork arms 365, will shift the block 369 to the right of Fig. 20, thereby compressing the spring 377. Continued movement of said block in this direction will cause a cam incline 381 on said block to engage a trigger 383 having a shoulder engaging one of the arms 375, and

thereby allow the spring 377 to shift the clutch member 337 sharply to the right. This will interrupt the downward movement of the weighing receptacle and initiate the 5 upward movement thereof.

As the weighing receptacle approaches the upward limit of its movement, the rollers 167 on the arms 165 will engage the fixed upper cams 169 and thereby rock the rods 10 159 and arms 157 and close the gates 155 of the weighing receptacle, so that the latter will be in readiness to receive the next charge of material to be fed thereto.

Next will be described suitable means for 15 automatically arresting the upward feed of the weighing receptacle. This means, in the present instance, comprises a rock lever 385 (Fig. 12), fast on a shaft 386 journaled in brackets 387 carried by one of the cross-bars 20 171 on the tower, said shaft having an arm 388 thereon connected by a rod 389 with an arm 390 fast on the rock shaft 358, referred to. The construction is such that as 25 the weighing receptacle approaches its upward limit of movement, the tappet 355 will engage the rock lever 385, and the latter through the shaft 386, arm 388, rod 389, arms 390, shaft 358, lever 357 and rod 361, will rock the crank 363, shaft 364 and forked 30 arm 365 in a direction to shift the block 369 to the left of Fig. 20 sufficiently to disconnect the bevel pinion 319 from the shaft 321, but not connect the bevel pinion 317 with said shaft.

35 As stated the bevel pinion 317 is connected to the shaft 321 by shifting the clutch member 337 to the left at the same time the clutch member 125 is shifted to the left. To accomplish this the trigger 305 (Fig. 40 40) and the corresponding trigger 373 (Fig. 20) may be fast on a cross rock shaft 394 (Fig. 17). The construction is such that the spring 379 is energized when the clutch member 337 is shifted to arrest the up movement of the weighing receptacle, but does 45 not become effective to shift the clutch member 337 to connect the bevel gear 317 with the shaft 321 until the trigger 393 is tripped with the trigger 305.

50 Having described the feed of a predetermined charge of material from the feed tubes into the weighing receptacle, and the discharge of the same into a bag at the filling station, next will be described means 55 for automatically causing the bag carrier to travel to convey the bag thus filled to the capping station. To accomplish this, one of the shafts 15, referred to, for the sprocket wheels of the bag carrier is provided with a gear 395 (Figs. 3 and 6) fast thereon meshing with a small gear 397 above the same on a stud shaft 399 mounted on one of the frames 3, referred to, said shaft having a bevel gear 401 fast thereon meshing with a

bevel gear 403 fast on a vertical stub shaft 65 which also has a bevel gear 405 thereon meshing with a bevel gear 407 on one end of a horizontal shaft 409 projecting into and journalled in a bearing in the clutch and gear box 105, so that said shaft is in alignment with the shaft 321 in said box.

To rotate the shaft 409 to feed the bag carrier at the times required, suitable clutch means may be provided, in the present instance, comprising a toothed member 411 70 fast on the shaft 321 and a companion member 413 fast on the shaft 409, and carrying a pin 415 urged by a spring 417 to the left of Fig. 20 to engage one of the spaces between teeth of the toothed member 411. The 75 spring-pressed pin 415 is normally held in retracted position so that it does not connect the members 411 and 413, by a latch 419 (Figs. 18 and 20) slidable in a boss 421 in the box 105, and urged upward by a coil 80 spring 423 in said boss. The latch 419 is connected by a yoke 425 with one arm of a bell-crank 427 fulcrumed on a pin 429 in the box 105. Co-operating with this bell-crank is a dog 431 mounted in a slot in the rod 85 371, referred to, and fulcrumed on a pin 433. This dog is yieldingly sustained in the path of the bell-crank 427 by a leaf spring 435 secured to said rod.

The construction is such that when the 90 rod 371 is shifted to the right of Fig. 20, the dog 431 will wipe idly past the bell-crank, but when the rod 371 is shifted to the left of Fig. 20, the dog 431 will engage the bell-crank and rock the latter and cause the yoke 100 425 to depress the latch 419 and allow the spring-pressed pin 415 to connect the members 411 and 413 (Fig. 18), thereby causing the shaft 321 to drive the shaft 409 and feed 105 the bag carrier.

It is desirable that the bag carrier should travel a predetermined distance sufficient to convey a bag from the filling station to the capping station, this travel in the present instance being obtained on one complete rotation of the gear 397. To automatically arrest the carrier after it has been fed this distance, the spring-pressed pin 415 (Figs. 18, 18^b and 20) is provided with a groove 110 415^a receiving the latch and having a cam face 415^b, the construction being such that on initial rotation of the clutch member 413 the pin 415 will be carried past the stationary latch and allow the latter to snap into an annular groove 415^c in the clutch member 413, so that when the pin 415 is brought around again to the latch its cam face 415^b 115 will wipe against a cam face 415^d (Fig. 18^b) on the latch and thereby retract the pin and disconnect the clutch members.

When the weighing receptacle has reached its upper limit of travel, the clutch member 337 is shifted to the left of Fig. 20 to inter-

rupt the upward feed, and in performing this operation, the rod 371 is shifted to the left of Fig. 20. As a consequence, the clutch connecting the shafts 421 and 409 for feed-
5 ing the bag carrier will be closed concur-
rently with the arrest of the upward move-
ment of the weighing receptacle.

Suitable means may be provided for automatically opening the gates 239 for the feed tubes as the bag just filled at the filling station approaches the capping station and an empty bag approaches the filling station. For this purpose, in the present instance, 10 each bag holder is provided with a lug 437 (Figs. 1 and 15) having an end 439 adapted to engage an arm 441 fast on the rock shaft 285, referred to, operatively connected with the toggle in the toggle box 233. The construction is such that as a bag holder containing an empty bag approaches the filling 15 station, the lug end 439 on the holder will engage the arm 441 and rock the same to the left of Fig. 15, thereby rocking the arm 283 and the link 281 to the right and straightening the toggle links 273 and 275. This will force down the block 277 connected to the plunger 263, compress the coil spring 269 and through the connections from said plunger to the gates for the feed tubes, will 20 open the said gates.

Since the crank 151 on the clutch and gear box 105 is operatively connected with the connections for controlling the gates of the feed tubes, this crank will be rocked in a 25 direction to cause the clutch member 125 to connect the sleeve shaft 115 with the main shaft 119, thereby starting the rotation of the feed screws concurrently with the opening of the gates for the feed tubes. This 30 movement of the clutch member 125 will automatically disconnect the sleeve shaft 331 from the main shaft, thereby arresting the shaft 321. The weighing receptacle will move downward from the weight of the material fed therein until a charge of predetermined weight has entered said receptacle, 35 when it is automatically arrested as described.

After a charge of material has been introduced into the bag at the bag filling station, the carrier is advanced to the capping station where a cap of paper or other suitable material is taken from a supply of caps and introduced into the bag on top of the charge of material therein. The upper face of the cap may have an adhesive coating thereon which may be moistened by a moistening device. Then portions of the bag may be folded down into adhesive engagement with the cap. Then the bag may be conveyed by the carrier to a third station where a waterproof adhesive may be applied to the portions of the bag which have been folded over at the previous station.

Then other portions of the bag may be 65 folded down onto the waterproof adhesive on the portions of the bag folded over at the previous stations.

This completes the closure of the bag, and effectively seals the same, so that ingress of 70 moisture into the material in the bag is prevented. Then the bags may be conveyed by the carrier from the third station and discharged from the carrier.

Since the mechanism for applying the 75 caps, for moistening the adhesive on the caps, for folding portions of the bag and rendering the bag watertight is shown and described in my said copending application, 80 it is unnecessary to show and describe the same in detail herein. The present application is more particularly concerned with the mechanism for weighing the charges and introducing the same into the bags at the 85 bag filling station.

There are important advantages in this bag filling mechanism. The materials are positively fed from the source of supply into the bags, and the charges are so lowered therein that puff of materials up from the bag is substantially prevented. As a consequence, a predetermined charge may be accurately weighed and introduced into the bag with economy of material, and the operative attending the machine is relieved 95 from the necessity of experiencing the discomfort of working in dusty atmosphere.

The operation of the machine will be readily understood from the foregoing description without further elucidation there- 100 of.

It will be understood that the invention is not limited to the specific embodiment shown, but that various deviations may be made therefrom without departing from the 105 spirit and scope of the appended claims.

What is claimed is:—

1. A machine of the character described, comprising, in combination, weighing means, a weighing receptacle supported by the 110 weighing means for movement into and out of a bag or container, means to feed material into said receptacle, means for effecting movement of the receptacle into a bag or container and nearly to the bottom thereof 115 to deposit the material therein, and valve means for controlling the discharge of material from said receptacle into said bag or container.

2. A machine of the character described, 120 comprising, in combination, a receptacle for receiving a charge of material and having a gate for closing its lower end, means for delivering material to the receptacle until the amount in the receptacle reaches a predetermined weight, means for supporting a bag or container beneath the receptacle, 125 means relatively to move the receptacle and

- support to introduce the receptacle into the movement of the receptacle for removing bag or container to deliver a charge of material bodily into the bag or container, and means for opening said gate while the 5 receptacle is in the bag or container to deliver the charge thereto from the receptacle.
3. A machine of the character described, comprising, in combination, a receptacle for receiving a charge of material and having a 10 discharge opening at its lower end and means for closing said opening, means for delivering material to the receptacle until the amount in the receptacle reaches a predetermined weight, a support for a bag or 15 container, means relatively to move said receptacle and support to introduce the receptacle into a bag or container to deliver a charge bodily into the bag or container, and means for opening the lower end of the 20 receptacle while in the bag or container to deliver the charge thereto from the receptacle.
4. A machine of the character described, comprising, in combination, a weighing receptacle for receiving a charge of material, weighing means for the receptacle means to support a bag or container, means by which the receptacle is adapted to move automatically into the bag or container in the course 25 of its weighing movement to introduce the charge into the bag or container, and automatic means operated independently of the weighing movement of said receptacle for effecting delivery of the charge from said 30 receptacle to the bag or container.
5. A machine of the character described, comprising, in combination, a receptacle for receiving a charge of material and supported for movement into a bag or container to deliver its charge into the same, means for controlling the movement of the receptacle into the bag or container to cause it to move gradually into the same until a charge of predetermined weight has entered the receptacle, 35 means for delivering the charge from the receptacle into the bag or container, and means for placing another bag or container in the charge receiving position.
6. A machine of the character described, comprising, in combination, a receptacle for receiving a charge of material, means for delivering a charge of predetermined weight into the receptacle, weighing means for determining the weight of the charge, means 40 for moving the receptacle and its charge into a bag or container nearly to the bottom thereof, means for opening the lower end of the receptacle within the bag or container to leave the charge in the bag or container when the receptacle is removed.
7. A machine of the character described, comprising, in combination, a weighing receptacle for receiving a charge of material, supporting means for a plurality of counterbalance weights, means actuated by 45
- supporting means to counterbalance material flowing into said receptacle, means cooperating with said weights for lowering the 70 weighing receptacle with its charge into a bag or container and nearly to the bottom of the bag or container, and means to deliver a charge of material determined by said weights from the receptacle into a bag 75 or container.
8. A machine of the character described, comprising, in combination, a weighing receptacle for receiving a charge of material, 80 weight means to counterbalance the weight of said receptacle, a plurality of counterbalance weights, supporting means for the latter, means actuated by downward movement of the weighing receptacle for progressively removing said counterbalance weights from said supporting means to retard the downward movement of said receptacle, means for lowering the weighing receptacle with its charge into a bag or container and nearly to the bottom of the bag 85 or container, and means to deliver a charge of material of a weight determined by said counterbalance weights from the receptacle into a bag or container.
9. A machine of the character described, comprising, in combination, a weighing receptacle for receiving a charge of material, counterbalance weights disposed upon opposite sides of the receptacle, a support 90 having steps for supporting said counterbalance weights at intervals, flexible connections between the receptacle and weights for progressively lifting the counterbalance weights from said steps as the receptacle moves downward, and means to deliver a charge of predetermined weight determined by said counterbalance weights from the receptacle into a bag or container.
10. A machine of the character described, comprising, in combination, a weighing receptacle for receiving a charge of material, a series of counterbalance weights, means to support said weights, a flexible member connected to said receptacle for progressively lifting said weights from their supporting means to retard the lowering movement of the receptacle as the material flows therein and to determine the weight of the charge, and means for lowering the weighing receptacles into a bag or container to deliver the charge of material from the receptacle into a bag or container.
11. A machine of the character described, comprising, in combination, a weighing receptacle for receiving a charge of material, a tube extending a substantial distance into the weighing receptacle and in which the material is confined until it approaches the lower portion of the receptacle, sets of counterbalance weights, means to support 110
- 120
- 130

- 5 said sets at opposite sides of said receptacle and with all the weights of a set in a row one above the other, guide wheels, and flexible members connected to said receptacle and 5 passing over said guide wheels for progressively removing said counterbalance weights from their supporting means in the course of the downward movement of the weighing receptacle.
- 10 12. A machine of the character described, comprising, in combination, a weighing receptacle for receiving a charge of material, sets of weights, tubes having provision for supporting the weights of said sets at intervals, guide wheels, flexible members connected to said receptacle and passing over said guide wheels into said tubes, and means cooperating with said flexible members for progressively lifting said weights from their 15 supports in the course of the lowering movement of said receptacle.
13. A machine of the character described, comprising, in combination, a weighing receptacle, upper and lower guide wheels at 20 opposite sides of said receptacle, chains or equivalent means arranged to pass about said upper and lower wheels, means connecting said weighing receptacle to said chains, sets of counterbalance weights, means to support said weights at intervals, and means cooperating with said chains for progressively lifting said weights from their 25 supports in the course of downward movement of the weighing receptacle.
- 30 14. A machine of the character described, comprising, in combination, a receptacle, a pair of feed tubes projecting into said receptacles, a hopper communicating with said feed tubes, a pair of feed screws for feeding material through said tubes to said receptacle, a support for said receptacle having provision for allowing lowering movement thereof as the material is fed therein, mechanism adapted to be operated upon the 35 delivery of a predetermined quantity of material to said receptacle, and means actuated by said mechanism for interrupting the flow of material from said tubes into said receptacle after a predetermined charge has entered the latter.
- 40 15. A machine of the character described, comprising, in combination, a receptacle for receiving a charge of material, feeding means projecting into said receptacle for feeding material thereto, valve means for said feeding means, supporting means for said receptacle having provision to allow downward movement thereof along said feeding means as the material enters the receptacle, mechanism adapted to be operated upon the 45 delivery of a predetermined quantity of material to said receptacle, and means actuated by said mechanism automatically to close said valve means to interrupt flow of material into the receptacle after a predetermined charge has entered therein.
- 50 16. A machine of the character described, comprising, in combination, a receptacle, means for feeding material projecting into said receptacle, means to allow said receptacle to move downward along said feeding means as the material is fed from said feeding means into said receptacle, mechanism adapted to be operated upon the delivery of a predetermined quantity of material to said receptacle, means actuated by said mechanism to cut off flow of material from said feeding means into said receptacle after a predetermined charge has entered the latter, and means to deliver the charge of material from the receptacle into a bag or container.
- 55 17. A machine of the character described, comprising, in combination, means for feeding material, a bag or container, a movably mounted weighing receptacle, means for variably resisting movement of the receptacle whereby its lower end will be adjacent the delivery end of the feeding means when a charge commences to enter said receptacle from said feeding means and adjacent the bottom of the bag or container when the complete charge has entered said receptacle, and means to deliver the charge from said receptacle to the bag or container.
- 60 18. A machine of the character described, comprising, in combination, means for feeding material, means to support a bag or container beneath said feeding means, a weighing receptacle receiving said feeding means and movable downward along the same into the bag or container to convey a charge of predetermined weight into the bag or container, weighing means for the receptacle, valve means to control the delivery of material from the feeding means to the receptacle, and valve means to control the delivery of the charge from the receptacle to the bag or container.
- 65 19. A machine of the character described, comprising, in combination, tubular means for feeding material, a weighing receptacle telescoping with said tubular means and movable downward along the same as material is fed therein, weighing means for the receptacle, feed screw means for forcing material through said feeding means into said receptacle, means automatically to arrest said feed screw means when a charge of material of predetermined weight has entered said receptacle, and a closure for the lower end of the receptacle and adapted to be opened to discharge material from the receptacle.
- 70 20. A machine of the character described, comprising, in combination, means for feeding materials, a receptacle for receiving the materials from said feeding means, gate

- means for controlling the discharge of materials from said feeding means to the receptacle, electrically controlled means for operating the gate means to close the latter when 5 a predetermined charge has entered the receptacle, and power operated means for lowering the receptacle to a position in which the materials are discharged therefrom and for raising the receptacle to a 10 charge receiving position.
21. A machine of the character described, comprising, in combination, a weighing receptacle provided with counter-balancing means, means to feed material into said receptacle, valve means for controlling the discharge of material from said feeding means to said receptacle, operating means for said valve means including a spring, toggle means for holding said spring in energized condition, and electrical means for causing said toggle means to release said spring and allow the latter to close said valve means on entrance of a charge of material of predetermined weight into said receptacle. 15
22. A machine of the character described, comprising, in combination, a weighing receptacle provided with counter-balancing means, means for feeding material into said receptacle, valve means to control the discharge of material from said feeding means into said receptacle, and operating means for said valve means including a plunger, a spring for actuating the same, toggle means cooperating with said plunger to hold said spring in energized position, and electrical means for buckling said toggle means to allow said spring to move said plunger and close said valve means on entrance of a charge of material of predetermined weight 20 into said receptacle.
23. A machine of the character described, comprising, in combination, a weighing receptacle provided with counter balancing means, feeding means telescoped into said receptacle, valve means for controlling the discharge of material from said feeding means into said receptacle, an operating member for said valve means extending between said feeding means and receptacle, and means cooperating with said operating member for automatically closing said valve means on entrance of a charge of material of predetermined weight into said receptacle. 25
24. A machine of the character described, comprising, in combination, a weighing receptacle provided with counter-balancing means, feeding means projecting into said receptacle, valve means for controlling the discharge of material from said feeding means into said receptacle, a pair of members extending between said feeding means and receptacle for operating said valve means, and actuating means cooperating with said members for closing said valve 30 means on entrance of a charge of material of predetermined weight into said receptacle. 65
25. A machine of the character described, comprising, in combination, a receptacle, means for feeding material into said receptacle, means for weighing the material, valve 70 means for controlling the discharge of material from said feeding means into said receptacle, means for automatically closing said valve means on entrance of a charge of material of predetermined weight into said receptacle, means positively actuated to lower the receptacle into a container in which the materials are to be deposited and to withdraw the receptacle from the container, automatically controlled valve means 75 for discharging the charge of material from the receptacle into the container, and means actuated automatically to open the first mentioned valve means to admit another charge of material into the receptacle after 80 delivering the first charge therefrom. 85
26. A machine of the character described, comprising, in combination, a receptacle, means for feeding material into said receptacle, valve means for said feeding means, counterbalance weights, means to support said weights at intervals, means to successively lift said weights from said supporting means in the course of downward movement of said receptacle as material is fed 90 therein, and operating means for said valve means including an electrical device rendered effective to close said valve means when the last of said weights is lifted from its 95 supporting means. 100
27. A machine of the character described, comprising, in combination, a weighing receptacle, means for feeding material therein, valve means for said feeding means, counterbalance weights, means to support said weights, means progressively to remove said weights from their supporting means in the course of downward movement of said receptacle, and operating means for 105 said valve means including an electrical circuit having a pair of contacts and a switch normally held open by the last weight lifted from its supporting means and automatically closed to render said operating means 110 effective to close said valve means when 115 said last weight is removed from its supporting means. 120
28. A machine of the character described, comprising, in combination, a receptacle, means for feeding material therein, valve means for controlling the discharge from said feeding means into said receptacle, valve means for controlling the delivery of the material from said receptacle into a bag 125 or container, positively actuated means for lowering the receptacle into a bag or container and for withdrawing it therefrom, a pair of fixed stops, and means carried

- by the receptacle and positioned to engage said stops and to be actuated thereby to open and close the valve means of the receptacle in the course of downward and upward movement respectively of the receptacle.
29. A machine of the character described, comprising, in combination, a weighing receptacle having weighing means, means for feeding material into said receptacle, valve means for said feeding means, valve means for said receptacle, a pair of fixed cams, means carried by said receptacle actuated by said cams on upward and downward movement of the receptacle for closing and opening the valve means for said receptacle, and means for imparting upward and downward movements to said receptacle to produce the operation of said valve means.
30. A machine of the character described, comprising, in combination, a weighing receptacle having a pair of gates at the lower end thereof, weighing means for the receptacle, a pair of members mounted on said receptacle and having elements for effecting opening and closing movements of said gates, actuating arms on said members, upper and lower fixed cams, and means for imparting upward and downward movements to said receptacle to cause said actuating arms to wipe along said cams and close and open said gates.
31. A machine of the character described, comprising, in combination, a weighing receptacle having weighing means, means for feeding material therein, means to allow downward weighing movement of said receptacle until a charge of material of predetermined weight has been fed therein, valve means for said receptacle, means for positively feeding said receptacle downward after the charge of predetermined weight has entered therein, and means operated in the course of the positive downward feed of the receptacle for opening said valve means to deliver the charge from said receptacle.
32. A machine of the character described, comprising, in combination, a weighing receptacle having weighing means, means for feeding material therein, means to allow downward movement of said weighing receptacle until a charge of material of predetermined weight has entered therein, valve means for said receptacle, means positively to feed said receptacle on downward after said charge has entered therein, means co-operating with said positive feeding means to open said valve means to deliver the charge from the receptacle, means positively to feed said receptacle upward after delivery of the charge therefrom, and means co-operating with said feeding means to close the valve means for said receptacle.
33. A machine of the character described, comprising, in combination, a weighing re-
- ceptacle, having a downward weighing movement until a charge of predetermined weight has entered said receptacle, means for feeding materials to the receptacle, weighing means for the receptacle, valve means for controlling the delivery of the charge of material from said receptacle, means for feeding said receptacle downward and upward including a shaft, pinions thereon, a gear meshing with said pinions, clutch means for connecting one of said pinions to said shaft to effect downward movement of the receptacle and to connect the other pinion to said shaft to effect upward movement of said receptacle, and means operated by said downward and upward movements of the receptacle for opening and closing the valve means for said receptacle.
34. A machine of the character described, comprising, in combination, a weighing receptacle provided with weighing means, means for feeding material into said receptacle, means to admit downward movement of said receptacle until a charge of material of predetermined weight has entered therein, means for imparting downward and upward movements to said receptacle including a shaft, a pair of pinions thereon, a gear meshing with said pinions, clutch means for connecting said pinions to said shaft, and operating means for said clutch means including a tappet on said receptacle, and elements in the path of said tappet, one of said elements being engaged by said tappet to shift the clutch means to connect the pinion to said shaft to effect downward movement of the receptacle, and the other element being engaged by said tappet to shift the clutch means to connect the other pinion to said shaft to effect upward movement of the receptacle, valve means for controlling the delivery of the charge from the receptacle, and means operated on the downward and upward movements of said receptacle for opening and closing the valve means of said receptacle.
35. A machine of the character described, comprising, in combination, a weighing receptacle provided with weighing means, means for feeding material therein, upper and lower wheels, a sprocket chain or equivalent means connecting said wheels and connected to said receptacle, means co-operating with said chain or equivalent means to admit downward movement of said receptacle until a charge of material of predetermined weight has entered therein, valve means for controlling the discharge of material from said receptacle, means co-operating with one of said wheels for moving said receptacle downward and then upward, and means operated in the course of said downward and upward movements for automatically opening and closing said valve means.
36. A machine of the character described,

- comprising, in combination, a weighing receptacle provided with weighing means, means for feeding material therein, valve means for controlling the discharge of material from said receptacle, upper and lower wheels, a sprocket chain connecting said wheels and connected to said receptacle, means co-operating with said chain or equivalent means to admit a charge of predetermined weight into said receptacle, means for imparting downward and upward movements to said receptacle, including a shaft, a pair of pinions thereon, a gear meshing with said pinions, means to impart rotation from said gear to one of the wheels for said sprocket chain, clutch means for connecting one of said pinions to said shaft to effect downward movement of the receptacle and to connect the other pinion to said shaft to effect upward movement of said receptacle, and means operable in the course of said downward and upward movements for opening and closing said valve means.
37. A machine of the character described, comprising, in combination, a receptacle, means including a feed screw for feeding material into said receptacle, means for weighing the material, valve means for controlling the discharge from said feed means into said receptacle, driving means for said feed screw including clutch means, means for automatically closing said valve means and shifting said clutch means to interrupt the operation of the feed screw on entrance of a charge of material of predetermined weight into said receptacle, and means for automatically opening said valve means and shifting said clutch means to operate the feed screw to deliver a succeeding charge of material into the receptacle.
38. A machine of the character described, comprising, in combination, a station having means for weighing charges of material of predetermined weight and delivering the same into bags or containers, a carrier having walled holders for the bags or containers thereon, each of said holders having a wall movable to admit a bag or container therein and permit discharge therefrom, means automatically to operate said member, and means to actuate said carrier to successively present the holders at said station.
39. A machine of the character described, comprising, in combination, a station having means for weighing charges of material of predetermined weight and delivering the same into bags or containers, a carrier having holders for the bags or containers thereon, each of said holders having opening and closing means for admitting the bags or containers therein and permitting the discharge thereof therefrom, means for feeding said carrier to successively present the holders at said station, and cam means for automatically operating the opening and closing means of the holders in the course of the transit of the carrier.
40. A machine of the character described, comprising, in combination, a station having means for weighing charges of material of predetermined weight and delivering the same into bags or containers, an endless carrier having holders for the bags or containers thereon, each of said holders having means adapted to open and close to admit and discharge the bags or containers, a cam path adjacent said endless carrier, and means including followers co-operating with said cam path for automatically operating the opening and closing means of the holders.
41. A machine of the character described, comprising, in combination, a station having means for weighing charges of material of predetermined weight and delivering the same into bags or containers, a carrier having holders for the bags or containers thereon, each of said holders having a movable wall for admitting and discharging the bags or containers, means for feeding said carrier to successively present said holders at said station, and means operable in the course of the transit of said carrier automatically to open and close said movable wall.
42. A machine of the character described, comprising, in combination, a station having means for weighing a charge of material of predetermined weight and for bodily introducing the weighed charge into a bag or container, a carrier having holders thereon for receiving the bags or containers, driving means for said carrier, and detector means for each of said holders for setting in operation means for arresting the carrier in case a holder approaching said station fails to receive a bag or container.
43. A machine of the character described, comprising, in combination, a receptacle mounted to receive a substantial vertical movement, a material feeding chute extending well within the receptacles, valve means at the lower end of said chute for controlling the delivery of materials therefrom, means for automatically closing said valve means upon delivery of a predetermined charge to the receptacle, means for determining the amount of said charge, and means for lowering said receptacle well within a bag or container and for discharging the charge in the receptacle into the bag or container.
44. A machine of the character described, comprising, in combination, a receptacle mounted to receive a substantial vertical movement, a material feeding chute extending well within the receptacles, valve means at the lower end of said chute for controlling the delivery of materials therefrom, means for automatically closing said valve means upon delivery of a predetermined charge to the receptacle, means for determining the

- amount of said charge, means for lowering said receptacle well within a bag or container and for discharging the charge in the receptacle into the bag or container, and means 5 for advancing bags or containers to the material receiving position.
45. A bag filling machine, comprising, in combination, a receptacle for receiving a charge of material, gate means for closing 10 the lower end of the receptacle, means for delivering a charge of material into the receptacle until the amount accumulated in the receptacle reaches a predetermined weight, means for automatically moving the 15 receptacle and its charge into a bag or container to approximately the bottom thereof, and means for automatically opening the gate means to deposit the charge of material in the bag or container below the air therein.
46. A machine of the class described, comprising in combination, a station having means for delivering a quantity of material of a predetermined weight into a bag or container, a carrier having holders for the bag 20 or container, each of said holders having a wall adapted to open and close to admit and discharge bags or containers, means for feeding the carrier to successively present the holders at said station, and means operable 25 in the course of the transit of the carrier automatically to open and close said wall to facilitate removal of a filled bag and insertion of an empty bag.
47. A machine for filling bags or contain- 30 ers with a pulverized material, comprising, in combination, a receptacle having approximately the size of the bag or container, means for lowering the receptacle into the bag or container to approximately the bot- 35 tom thereof, means for delivering pulverized material to the receptacle until the amount in the receptacle reaches a predetermined weight, and means at the lower end 40 of the receptacle for releasing the material from the receptacle to deposit the pulverized material in the bag or container below the air therein.
48. A machine for filling bags or contain- 45
- ers with a pulverized material, comprising, in combination, a receptacle for pulverized material, having a gate for closing its lower end, means for lowering the receptacle into a bag or container to approximately the bottom thereof, means for delivering pulverized material to the receptacle until the 50 amount in the receptacle reaches a predetermined weight, and means for controlling said gate and operable to open the gate while the lower end of the receptacle is near the bottom of the bag or container to deposit the pulverized material in the bag or container below the air therein.
49. A machine for filling bags or contain- 55 ers, comprising, in combination a receptacle for a charge of material, means for introducing the receptacle into a bag or container to approximately the bottom thereof, means for delivering material to the receptacle until the amount in the receptacle reaches a predetermined weight, and means for retaining the charge of material in the receptacle until the latter approaches the bottom of the bag or container and then dis- 60 charge the material in the bag or container below the air therein.
50. A machine for filling bags or contain- 65 ers, comprising, in combination, a receptacle for a charge of material and mounted for sliding movement into and out of a bag or container, means for automatically lowering the receptacle into a bag or container to approximately the bottom thereof, means for automatically delivering material to the receptacle until the amount in the receptacle reaches a predetermined weight, means for retaining the charge of material in the receptacle until the latter approaches the bottom of the bag or container and then dis- 70 charging the material in the bag or container below the air therein, and mechanism 75 for automatically removing the receptacle from the bag or container.

In testimony whereof I have signed my name to this specification.

CHARLES H. HOWARD.
